UNITED STATES PATENT OFFICE

110,351

DESIGN FOR A COMBINED GLOBE AND MOUNTING

Raymond R. Dupler, Toledo, Ohio

Application May 24, 1937, Serial No. 69,519

Term of patent 7 years

To all whom it may concern:

Be it known that I, Raymond R. Dupler, a citizen of the United States, and resident of Toledo, Lucas County, Ohio, have invented a new, original, and ornamental Design for a Combined Globe and Mounting, of which the following is a specification, reference being had to the accompanying drawing, forming a part thereof.

In the drawing:

The figure is a front perspective view of the combined globe and mounting showing my new design.

I claim:

The ornamental design for a combined globe and mounting as shown.

RAYMOND R. DUPLER.
